(57) **CLAIM**

I claim the ornamental design for an expanded metal trash receptacle, as shown and described.

DESCRIPTION

FIG. 1 is a perspective view of an expanded metal trash receptacle illustrating my new design;

FIG. 2 is a top plan view thereof;

FIG. 3 is a bottom plan view thereof;

FIG. 4 is a right-side elevational view thereof, with the undisclosed left-side elevational view being a mirror image of that illustrated; and,

FIG. 5 is a front elevational view thereof with the undisclosed rear elevational view being identical to that illustrated.
